UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed April 2, 1925. Serial No. 20,118.

My invention relates generally to internal combustion engines and has for its principal object the provision of an improved piston valve structure for effecting the admission 5 function for internal combustion engines.

It is understood by those familiar with the operation of internal combustion engines where the conventional carburetion means is used for fuel metering to the air and where 10 ducts are used for the passage of the mixture to the inlet valves of the cylinders that, during light load operation, when the volume inducted is low and the ducts large enough to permit high volume efficiency at 15 full load engine operation, the low volume movement through the large ducts, fails to provide sufficient volume velocity; to prevent the liquid parts metered to the air at the carburetor from dropping or falling out of 20 the air stream and collecting in pools on flat surfaces or in drainage traps that may be formed in the bottoms of the ducts.

Further, it is understood that when the throttle is opened suddenly and the volume 25 inducted through the ducts is increased, and the velocity of flow of said volume is increased, the liquid collected on the bottom surfaces of the duct will be swept into the cylinders in liquid form, thereby greatly 30 retarding combustion, contaminating the lubrication of the engine and materially decreasing acceleration and engine performance.

Therefore, it is the object of my invention 35 to provide an inverted form of duct that leads from the metering device or carburetor, to the top of the cylinder or barrel of the piston valve with the ports that are formed in the piston valve cylinder connecting the 40 chamber within the piston valve cylinder and said inverted inlet duct with an annular chamber formed around the piston valve cylinder, said duct leading on one side to the engine cylinder to which the fuel mixture is 45 to be inducted and the floor of this annular chamber that surrounds the piston valve cylinder and joins the piston valve ports with the induction cylinder being inclined downwardly toward said induction cylinder chamber, 50 thereby providing drainage at all times by gravity to the induction cylinder, regardless of charge induction velocity.

With the foregoing and other objects in view, my invention consists in certain novel

features of construction and arrangement of 55 parts that will be hereinafter more fully described and claimed and illustrated in the accompanying drawings in which:

Fig. 1 is a vertical section taken through the center of an engine that is equipped with 60 my improved piston valve structure.

Fig. 2 is a horizontal section taken on the line 2—2 of Fig. 1.

Referring by numerals to the accompanying drawings, 1 designates a cylinder block 65 in which is formed a bore having two diameters, that portion of the bore having the smaller diameter functions as a combustion chamber 11 and the portion having the larger diameter functions as a charge pumping chamber 12.

Arranged for reciprocatory movement within the chambers 11 and 12 is a two diameter piston 13 that is connected in the usual manner by a connecting rod 14 to the 75 crank or throw of a crank shaft 15.

The charge volume to combustion chamber 11 is admitted through inlet ports 16, the latter being located in a plane where they are uncovered and open only when piston 13 80 is at the lower or outer end of its stroke.

Leading from the upper end of pumping chamber 12 is a port 17 that permits the outlet of gaseous fuel or charge volume from 85 said pumping chamber.

Formed integral with or fixed to the side 90 of cylinder 10, is a relatively short piston valve cylinder or barrel 18, within which is arranged for reciprocative movement, a piston valve 19. This piston valve is connected in the usual manner by connecting rod 20 to an eccentric or crank shaft 21, that is mounted for operation in suitable bearings 95 and which is adapted to be driven, in any suitable manner at engine speed, or at the same speed with crank shaft 15.

One end of an inverted U-shaped duct 22 communicates directly with the upper end 100 of the valve chamber within cylinder 18 and the other end of this duct is in direct communication with a source of gaseous fuel supply, for instance, a carburetor.

Formed in the wall around the upper portion of valve cylinder 18 is an annular chamber 23, and leading therefrom through the 105 wall of cylinder 10 and communicating with the upper portion of the pump chamber 12 is a port 24.

Leading from the annular chamber 23, through the wall of cylinder 18 and communicating directly with the piston valve chamber, is a series of ports 25, the same occupying a plane where they are uncovered and open only when piston valve 19 is at the lower end of its stroke.

All portions of the surface of the floor at the bottom of the annular chamber 23 decline gradually toward port 24, that enters the pumping chamber 12 and, as a result of this construction, any drops or particles of liquid that might otherwise tend to accumulate on the surface at the bottom of the annular chamber will flow by gravity downward over said inclined surface and discharge through port 24 into pumping chamber 12.

It will be understood that the cranks to which piston 13 and piston valve 19 are connected, are disposed so that piston valve starts to move downward slightly in advance of the initial downward movement of piston 13, so that as piston 13 continues to move downward, gaseous fuel is drawn from the carburetor through inverted U-shaped duct 22, into the upper portion of the piston valve chamber from thence through ports 25, and thence through annular chamber 23 and port 24 into pumping chamber 12.

Thus, from the top of the inverted U-shaped duct 22, the flow of incoming gaseous fuel to pumping chamber 12 is in a general downward direction and, as a result, any condensation or any drops or particles of liquid that might separate from the inflowing gaseous fuel will, by gravity and the force of the flow of gas through the piston valve chamber be carried directly into the pumping or charge induction cylinder chamber 12.

From chamber 12, the inducted gaseous fuel will, on the upward stroke of piston 13 be forced out thru port 17 and thence thru a suitably arranged duct (not shown) into

an adjacent combustion chamber, therein to be compressed and ignited so as to force the piston therein downward on its power stroke.

For a more detailed description of the operation of the structure herein shown and described, reference may be had to U. S. Letters Patent No. 1,511,707, issued October 14, 1924.

It will be understood that, during the upward or compression stroke of the piston 13, piston valve 19 closes ports 25, so as to cut off the passage of gaseous fuel from duct 22 into annular chamber 23 and into pumping chamber 12.

Thus it will be seen that I have provided a piston valve structure for effecting, in an advantageous and efficient manner, the charge admission function to the pumping or induction chamber of an internal combustion engine.

It will be understood that minor changes in the size, form and construction of the various parts of my improved internal combustion engine may be made and substituted for those herein shown and described without departing from the spirit of the invention, the scope of which is set forth in the appended claim.

I claim as my invention:

In an internal combustion engine, a piston valve cylinder, open at its upper end for the reception of gaseous fuel, the wall of said cylinder being provided with an annular chamber having an outlet on one side, so the bottom surface of which annular chamber declines toward said outlet, said annular chamber having communication with the chamber within the piston valve cylinder by means of ports formed through the inner portion of the valve cylinder wall and a piston valve arranged for reciprocatory movement within said valve cylinder.

In testimony whereof I affix my signature.
EVERETT R. BURTNETT.
